UNITED STATES PATENT OFFICE.

OSCAR H. PIEPER AND ALPHONSE F. PIEPER, OF ROCHESTER, NEW YORK.

ELECTRIC MOTOR.

No. 868,806.

Specification of Letters Patent.

Patented Oct. 22, 1907.

Application filed November 25, 1905. Serial No. 289,140.

To all whom it may concern:

Be it known that we, OSCAR H. PIEPER and ALPHONSE F. PIEPER, of Rochester, county of Monroe, and State of New York, have invented certain new and useful 5 Improvements in Electric Motors; and we do hereby declare the following to be a full, clear, and exact description of the same, reference being had to the accompanying drawings, forming a part of the specification, and to the reference-numerals marked thereon.

10 Our present invention relates to electric motors and it has for its object to provide certain improvements therein whereby the parts may be made compact and readily assembled and adjusted in a casing which completely incloses them, and it has for its further object to 15 provide an improved form of governing or controlling device to be employed in connection with the motor which will automatically control its speed and which may also be confined within the casing.

To these and other ends the invention consists in 20 certain improvements and combinations of parts all as will be hereinafter more fully described, the novel features being pointed out in the claims at the end of the specification.

In the drawings: Figure 1 is a side elevation showing 25 a motor constructed in accordance with our invention, a portion of the side of the frame or casing being removed to disclose the commutator end of the armature shaft. Fig. 2 is a cross sectional view taken on the line 2 $\times$ 2 $\times$ of Fig. 3, and Fig. 3 is a horizontal sectional view. 30 Fig. 4 is a detail view partly in section, showing a portion of the adjusting mechanism of the governing or controlling device. Fig. 5 is a detail sectional view taken on the line 5 $\times$ 5 $\times$ of Fig. 3. Fig. 6 is a perspective view of one of the shaft bearings, and Fig. 7 is a detail 35 side elevation of one of the brush holders.

Similar reference numerals in the several figures indicate similar parts.

A motor embodying our invention comprises an outer casing or shell 1 preferably cylindrical in form and provided with a plurality of inwardly extending ribs 2 which are spaced equidistantly and adapted to center the field magnet 3 which is provided with depressions or recesses receiving the ribs 2, as shown in Fig. 2. The ends 4 of the casing 1 extend over the sides of the field 45 magnet and are dome-shape, one of the ends indicated by 4', being detachable to permit the removal and insertion of the field magnet. The central portions of the ends are formed by circular head pieces 5, 5', provided with bosses 6 carrying sleeves 7 in which the armature shaft 8 is journaled. The latter is provided at 50 points adjacent the inner sides of the heads with relatively stationary abutments such as collars 9 and 10 which prevent its longitudinal movement by engagement with the proximate ends of the sleeves 7. At the 55 outer ends of each sleeve a channel 15 is formed in which engages an adjusting member such as 16 of a

screw 17 located in a threaded aperture in the corresponding boss 6 and which may be adjusted therein to move its sleeve longitudinally on the armature shaft into engagement with the shaft abutments to limit the longitudinal movement of the armature. In order to facilitate the application and removal of the sleeves they are provided at the ends of the slots or channels 15 with semi-circular recesses or notches 18 which are adjusted into alinement with the screw aperture and after the screw has been inserted therein, so that its head lies in the channel 15, the sleeves are given a partial location locking them securely to their respective adjusting members. This is a convenient means of securing the bearing sleeves or bushings as they may be accurately adjusted either inwardly or outwardly by rotating their adjusting members 17.

The armature of the motor, indicated by 19, is provided at one end with the usual commutator rings or sections 20 with which coöperate the brushes 25—25*. In order to facilitate the adjustment of the latter to the correct position on the armature to overcome the disadvantages resulting from sparking, they are supported upon a segmental arm 26 guided in a way formed on the head 5 to which it is adjustably secured by 80 screws 27 passing through an elongated aperture 28. Each brush is held in a clip or holder 30 which is pivotally secured to the end of the arm 26 by a post 31 and is operated toward the commutator by a spring 32. The arm 26 and the guide in which it is supported 85 are both formed concentric with the commutator thereby permitting the arm to be rotated and the brushes carried through a wide angle of movement while in contact with the commutator.

The governor or controlling device which I employ 90 and have shown as illustrating my invention is located in proximity to one end of the armature and is preferably carried upon the sleeve 10, secured to the shaft 8, which has an outwardly extending annular flange 35 rigidly supporting an insulated contact plate or ring 95 36. The sleeve 10 may be permanently connected to the shaft 8 if desired, but for convenience in assembling the parts connected thereto I prefer to form it separate from the shaft and secure it against rotary movement thereon by providing its inner end with 100 one or more projections 11 which interlock in recesses formed in the end of the usual enlargement 12 on the armature shaft. Mounted on the face of said plate and also insulated therefrom is a second contact plate or ring 37 and coöperating respectively with these rings 105 36^a 37^a are brushes 36^a 37^a which are mounted in tubular supports 38 carried on the head 5'. Projecting laterally from the respective supports are contact fingers 36^b and 37^b, which when the head 5' is in normal position, contact with fingers 36^c and 37^c, projecting laterally 110 from an insulating block 39 secured at one side of the part 4' of the motor casing, and to which the wires

forming the motor circuit are connected, as will be more fully described hereinafter.

The rings 36 and 37 rotate with the armature, and they are normally in electrical connection through 5 contact points 40-41, one of which is carried on a movable member 42 journaled on the ring 37 and adapted to be operated outwardly by the centrifugal force imparted to it from the motor shaft. This member 42 is arranged at one side of the sleeve 10, and at 10 the other side of the latter are small rigidly projecting guide arms 43, between which is supported a bar 44, connected at its ends, by springs 45, to the projecting ends of a pin or cross bar 50 secured to the member 42. Resting on the side of the sleeve at each side of the arms 15 43 are notched or stepped adjusting blocks or slides 51, rigidly supported on the side of the ring 52, and having their ends projecting beneath the ends of the bar 44. These blocks or slides are each provided with a plurality of steps a, b and c, arranged one above the 20 other and adapted, as the block is advanced beneath the bar, to move it outwardly different distances relative to the member 42 to increase the tension of springs 45, as will be understood. The ring 52 surrounds the outer end of the sleeve 10 and is provided with an annular channel in which rest pins 53 in the two ends of a bifurcated adjusting arm 54 which is attached, by 25 means of screws 55, to the end 56 of a bell crank lever 57, journaled upon a bracket 58 within the end 4' of the motor casing. The other end 59 of the bell crank lever 30 projects into a rectangular box portion 60, at one side of the motor casing which is normally closed by a removable cover plate 61 and contains the operating devices for adjusting the governor and controlling the motor circuit. The operating devices comprise a shaft 35 62 journaled in the sides of the box, as shown in Fig. 4, having an outwardly extending end provided with an operating knob or handle 63, in which is a spring operated pin 64 having the projecting end coöperating with a series of indentations or apertures provided in 40 a plate 65 to temporarily secure the parts in adjusted position, as will be understood.

Arranged upon the shaft 62 is a cam member 70 having a series of operating shoulders or projections a', b', c', arranged at progressively increasing distances 45 from the shaft which are proportioned relatively to the notches a, b and c on the blocks or slides 51 so that as they successively engage the end 59 of the bell crank lever, or the roller 59' located thereon, the block 51 will be moved a corresponding distance on the 50 sleeve 10. In rear of each of the projections the cam is provided with shallow recesses 71 which allow the bell crank lever, after it is operated to adjust the blocks or slides 51 to the desired position, to drop backwardly a sufficient distance to remove the adjusting ring 52 from frictional engagement with the end of the block, and also to center the pins 53 midway between the side shoulders of the annular recess in the ring. That portion of the cam in rear of the projection c', and its recess 71, is rounded as indicated at 72 for 55 the purpose of allowing the end of the lever 59 to return gradually and retract the blocks or slides 51 if the operator desires to arrest the motor when it is operating at its highest speed. This is an advantageous arrangement of the parts, for it will be seen that after the governing devices have been set to produce the desired

speed, by a regulation of the tension of the springs 45, there is no friction between the relatively stationary parts of the adjusting device and those which are mounted on the armature shaft and by restoring the tension devices to their normal position when the motor circuit is broken it is then only possible to start the motor, at some subsequent time, at its lowest rate of speed. In order to break the motor circuit, to arrest the motor, only when it is operating at the lowest speed, I provide a movable contact member which is 75 arranged relatively to stationary contacts, included in the motor circuit, which is automatically disengaged after the controlling devices are operated to reduce the speed of the motor to the lowest point. Upon the controlling shaft 62 is a cylindrical insulated contact member 73 having at one side a flat face 73^a which is disposed relatively to the cam projections a', b', c', so that when the cam 70 is in the position shown in Fig. 3 the contact between the member 73 and the spring fingers 36^a and 37^a, projecting thereover, will be broken. To 80 enable the member 73 to be rotated a partial revolution into engagement with the aforementioned contact fingers without imparting any movement to the end 59 of the bell crank lever, a portion of the cam 70 lying at the base of the projection a' is made concentric with the 85 shaft 62, as indicated by 74.

The motor circuit in which the controlling or governing devices are arranged is shown diagrammatically in Fig. 7, which for the purpose of illustration shows a direct current series type motor comprising the field 95 coils 3^a connected to the supply conductor A and which are connected in series with the armature 19 by extending their terminal 75 to the brush 25, the other brush 25^a being connected indirectly with the other supply wire B' which is attached to the contact finger 100 36^a. The intermediate portion of the circuit comprises the contact finger 37^a, the conductor 80 leading therefrom to the contact 36^a and the conductor 81 leading from the brush 25^a to the contact finger 37^a it being understood that the contact plates or rings 36 and 37 105 are normally in electrical connection through the points 40 and 41 and that when the brushes 36^a and 37^a engage said rings their respective arms 36^b and 37^b engage the contacts 36^c and 37^c and that the circuit may be opened and closed manually by the rotation of the 110 member 73 into and out of engagement with the spring fingers 36^d and 37^d.

The operation of the various parts of the motor constructed in accordance with my invention will be readily understood from the foregoing description. 115 However, when it is desired to regulate the motor, the operator rotates the knob or handle 63 moving the cam 70 in the direction indicated by the arrow in Fig. 3, first causing the contact member 73 to engage the fingers 36^d and 37^d when the electric current enters the 120 motor and traverses the following circuit: Conductor A, field magnet coils 3^a, conductor 75, brush 25, when after traversing the coils of the armature the current 19 passes through the brush 25^a, conductor 81, spring contacts 37^e and 37^b, brush 37^a, ring 37, thence through the 125 contact points 40, 41, ring 36, brush 36^a, spring contacts 36^b and 36^c, conductor 80, contact finger 37^d, the member 73, and finger 36^d completing its course through the conductor B. When the cam 70 stands in this position of adjustment the motor is operated at its 130

lowest speed. Any increase thereof over a given number of rotations of the armature shaft per minute causes the contact member 41 to be disengaged from the member 40 to break the motor circuit, until the speed of the 5 armature is reduced when the circuit is automatically closed. If a higher speed is desired the operator may successively rotate one or more of the projections a' , b' , c' , beneath the end 59 of the bell crank lever moving it outwardly against the tension of its spring 74 to 10 cause the slides 51 to be correspondingly adjusted to raise the bar 44 and increase the tension of the springs 45 which control the outward movement of the member 42 and permit the armature to revolve at a greater speed.

15 A motor constructed in accordance with my invention may be made compact and the operating parts being inclosed are protected from accidental injury. The adjustable bearing sleeves for the armature shaft permits the armature to be accurately centered and 20 held against longitudinal movement and further, the sleeves being separate from the supporting frame or casing, they may be readily replaced when they become worn, thus enabling the pole pieces of the field magnet to approach very closely to the circumference 25 of the armature.

By arranging the parts of the governing or controlling mechanism as I have described them, those associated with the sleeve 10 may be assembled thereon and readily secured to the armature shaft in the first instance or detached therefrom for the purpose of repair.

I claim as my invention:

1. In a controlling device for an electric motor, the combination with an armature shaft and contact plates mounted thereon, of a movable contact member normally connecting said plates, a tension device attached to said member and movable in a direction transversely of the armature shaft, and a member movable longitudinally of the shaft and coöperating with the tension device, means for operating it and a motor circuit leading to the contact plates.

2. In a controlling device for an electric motor, the combination with an armature shaft and contact plates mounted thereon, of a movable contact member normally connecting said plates, an adjusting member movable longitudinally of the shaft and an extensible tension member operated thereby and connected to the movable contact member, means for operating the adjusting member and a motor circuit leading to the contact plates.

3. In a controlling device for an electric motor, the combination with an armature shaft and contact plates mounted thereon, of a movable contact member normally connecting said plates, an extensible tension device connected to the movable contact member and an adjusting member provided with a plurality of graduated steps coöperating with the tension device, means for operating the member and a motor circuit leading to the contact plates.

4. In a controlling device for an electric motor, the combination with an armature shaft and contact plates mounted thereon, of a movable contact member normally connecting said plates, an extensible tension device connected to the movable member and comprising a bar arranged transversely of the armature shaft and an adjusting member operating said bar relatively to the shaft, means for operating the member and a motor circuit leading to the contact plates.

5. In a controlling device for an electric motor, the com-

bination with an armature shaft, a sleeve thereon provided with a transversely extending guide, insulated contact plates and a contact member normally connecting them, of a tension device connected to said member and lying in the 70 guide on the sleeve, an adjusting member supported on the latter and coöperating with the tension device, means for moving said member and a motor circuit leading to the contact plates.

6. In an electric motor controller, the combination with 75 an armature shaft, insulated contact plates thereon and a movable member normally connecting them, a tension device connected to the member and a regulating member co-operating with the tension device and provided with a plurality of steps, of adjusting mechanism comprising a 80 cam having shoulders corresponding to the steps on the regulating member, operating connections between the latter and the cam and a motor circuit leading to the contact plates.

7. In an electric motor controller, the combination with 85 an armature shaft, contact plates located thereon and a movable contact member normally connecting them, of a tension device connected to said member, a regulating member co-operating therewith and adapted to be moved into different positions to adjust the tension device, mechanism for adjusting the regulator comprising a revolute 90 cam having a plurality of operating projections and provided with recesses in rear thereof and a motor circuit leading to the contact plates.

8. In an electric motor controller, the combination with 95 an armature shaft, contact plates located thereon and a movable contact member normally connecting them, a tension device connected to said member and a stepped regulating member co-operating therewith and supported on the armature shaft, of a ring mounted on the latter and engaging the controlling member, an arm co-operating with the ring and a cam engaging the arm having projections corresponding to the steps on the controlling member, means for holding the arm in engagement with the cam and a motor circuit leading to the contact plates.

9. In an electric motor controller, the combination with 100 a field, an armature and an armature shaft, of a sleeve removably supported on the shaft, contact plates on the sleeve and a movable member normally connecting them, an extensible tension device connected to the member and 110 a ring mounted on the sleeve, a regulating member carried on the ring and co-operating with the tension device, means for adjusting the ring and a motor circuit leading to the contact plates.

10. In an electric motor controller, the combination with 115 a field, an armature and an armature shaft having a projection thereon, a sleeve on the shaft interlocking with said projection and contact plates supported on the sleeve, of a movable member normally connecting them arranged at one side of the sleeve, a tension device connected to the member and extending over the other side of the sleeve, and a regulating member carried on the sleeve and coöperating with the tension device, means for adjusting said member and a motor circuit leading to the contact plates.

11. In an electric motor controller, the combination with 125 a field, an armature and an armature shaft, a sleeve removably supported on the shaft and contact plates supported on the sleeve, of a contact member normally connecting them, a guide on the sleeve and a tension device connected to the contact member having an adjustable 130 part supported in said guide, a ring on the sleeve and regulating member on the ring coöperating with the adjustable part and extending at opposite sides of the guide, means for adjusting the ring and a motor circuit leading to the contact plates.
